(57) **CLAIM**

The ornamental design for a dust separator part as shown and described.

DESCRIPTION

FIG. 1 is a front perspective view of a dust separator part in accordance with our new design;

FIG. 2 is a rear perspective view of the dust separator part of FIG. 1;

FIG. 3 is a front elevation view of the dust separator part of FIG. 1;

FIG. 4 is a rear elevation view of the dust separator part of FIG. 1;

FIG. 5 is a left-side elevation view of the dust separator part of FIG. 1;

FIG. 6 is a right-side elevation view of the dust separator part of FIG. 1;

FIG. 7 is a top plan view of the dust separator part of FIG. 1; and,

FIG. 8 is a bottom plan view of the dust separator part of FIG. 1.

The portions of the dust separator part shown in broken lines in the figures depict unclaimed environmental subject matter, are for illustrative purposes only, and form no part of the claimed design.
